UNITED STATES PATENT OFFICE.

JOHAN AUGUST ZINN, OF ALTOONA, PENNSYLVANIA.

HYDRAULIC SWITCH AND SIGNAL APPARATUS.

SPECIFICATION forming part of Letters Patent No. 449,240, dated March 31, 1891.

Application filed October 18, 1887. Serial No. 252,695. (No model.)

To all whom it may concern:

Be it known that I, JOHAN AUGUST ZINN, of Altoona, county of Blair, State of Pennsylvania, have invented a new and useful Improvement in Switch and Signal Apparatus, of which the following is a true and exact description, due reference being had to the accompanying drawing, which forms a part thereof.

10 My invention has reference to switch and signal apparatus; and it consists in certain improvements, all of which are fully set forth in the following specification, and shown in the accompanying drawing, which forms part thereof.

15 This invention relates to a construction of hydraulic switch and signal apparatus set out in my application, Serial No. 224,818, and filed January 19, 1887. In that application 20 the switches or signals are operated by a plunger working in a cylinder, which cylinder receives a liquid, and said liquid is caused to flow under pressure in a manner to eject the plunger. The pressure is caused by 25 pumping it through an accumulator, and the flow of the liquid is controlled by means of a suitable valve device, which in practice is connected with the interlocking mechanism. The liquid flows through pipes, and in returning 30 the plunger to reset the switch or signal the actuating-liquid which has passed through a valve device is allowed to escape through a stand-pipe into a tank maintaining a constant pressure, such as is necessary for keeping 35 all of the operative compartments or tubes full of the operating-liquid. In this application my object is to employ the same system combined with an additional feature whereby in returning the switch or signal to its normal position gravity or springs shall not be relied upon, but instead a hydraulic device 40 shall be resorted to to act upon the plunger in the opposite direction to that in the other cylinder.

45 In carrying out my invention I arrange two cylinders, preferably in line, with a double-ended plunger common to both cylinders, whereby if a plunger enters one cylinder it is drawn out of the other, and vice versa.

50 This plunger is connected directly or indi-

rectly to a switch or a signal. One of these cylinders connects with the hydraulic mechanism above described and set out in my application above referred to, and the other of said cylinders connects with a second accumulator of less power than the one in the system for positively operating the switch or signal. From this construction it is evident that when the stronger accumulator, or that connecting with the interlocking mechanism, 55 is in operative connection with one of the cylinders at the switch or signal the plunger is forced into the other cylinder, returning the liquid from said cylinder back into a main connecting with the smaller accumulator, 60 the piston thus acting by means of a differential pressure upon its two ends. When the stronger accumulator is cut out of action and the actuating-liquid allowed to flow into the stand-pipe, then the weaker accumulator comes into action and returns the plunger to its normal position. It is evident 70 that this double construction of cylinders is nothing more or less than the equivalent of a single cylinder with the pressure of the two 75 accumulators upon the respective sides of the piston.

In the drawing is shown a diagrammatic view giving the relation of the operating parts and illustrating the invention as applied to both a switch and a signal.

A is the force-pump, which draws a supply of liquid from the tank S by means of a pipe U. This liquid is pumped by means of pipes B and M into the accumulators C and N. 85 Pipe M is normally closed by a stop-cock m, and liquid is only admitted into the accumulator N when the liquid is low and needs to be replenished. The accumulator C, being more heavily loaded than the accumulator N, 90 consequently exerts the greater pressure. The liquid forced through the pipe B enters the valve-box D with the pressure of the accumulator C, and if the lever d is thrown to the position indicated the valve E will be 95 opened and valve F closed. This will allow the liquid to flow from pipe B through valve E into the pipe G, and thence act upon a piston h in a cylinder H. Connecting with this cylinder H upon the other side of the piston h 100

is the line-pipe I, which extends from the signal-house to the switch or signal operating mechanism J. The pipe M, connecting with the smaller accumulator, extends to the 5 switch or signal operating mechanism J; but said pipes I and M connect with separate cylinders.

Referring now to the switch or signal operating mechanism, preferably arranged directly at such switch or signal and marked J in the drawings, we have the two cylinders J' and J², with a plunger K, the ends of which project into said cylinders, so that when the plunger is pushed out of one cylinder it is 10 received into the other cylinder, and vice versa. To the plunger K is connected a cross-head k, which is bolted to the bar l, connecting the points of the switch L, or in case of the signal O this cross-head k is connected to the 15 vertical rod P, which in turn operates the semaphore-arm R. The semaphore-arm R is counterbalanced by a weight r, so as to be easily moved in either direction. As shown in the drawing, the pipe I connects with the 20 switch-operating device and with the signal-operating device by means of the pipe i, and likewise the pipe M connects also with the signal-operating device by a pipe m. This is correct if the signal O and the switch L are 25 operated together, or, which often is the case, two or more signals or two or more switches by one lever; but in case where a signal is to be operated alone then the switch device would be removed entirely, or vice versa.

30 T is the stand-pipe, which, when the valve E is closed and F is open to cut off the liquid from the accumulator C, receives the liquid from pipe G through valve F and discharges it into the tank S with a uniform back-pressure.

35 So far as the invention is concerned, it is evident that the liquid from pipe G might pass directly into pipe I; but where a number of switches and signals are to be operated on the interlocking principle it is found necessary to use the intermediate piston h, which controls the flow of oil or other liquid in the pipe I. The particular specific function of this piston and its connections is clearly 40 shown and claimed in my application above referred to, and in this application I make no claim to this construction, other than that the same is necessary to the operativeness of this device.

45 It is evident that the cylinder J' receives the pressure of the accumulator C, whereas the cylinder J² receives the pressure of the accumulator N, and when both of these accumulators are in active operation then the 50 plunger K moves in view of the differences in the pressures. When the valve E is closed and F opened, the accumulator N is the only one in operation, and that operates against the pressure in the stand-pipe T alone, and 55 with a positive force returns the switch or signal, or both, to their normal or initial position. It is immaterial to my invention what

the details of construction may be or whether or not the interlocking devices be used or not.

Having now described my invention, what I claim as new, and desire to secure by Letters Patent, is—

1. In a switch or signal operating device, the combination of the switch or signal, a plunger or piston for actuating said switch or signal, a pipe-line for supplying a pressure-liquid to one side or end of the plunger or piston, a pipe-line for supplying a pressure-liquid to the other side or end of the plunger or piston, a pressure device to supply said liquid to each of said lines of pipe, but under different pressures, an overflow stand-pipe, and a valve device for allowing the liquid from the pipe having the greatest operative pressure to pass into the overflow-pipe, reducing the pressure in the pipe having the greatest operative pressure.

2. In a switch or signal operating device, the combination of the switch or signal, a plunger or piston for actuating said switch or signal, a pipe-line for supplying a pressure-liquid to one side or end of the plunger or piston, a pipe-line for supplying a pressure-liquid to the other side or end of the plunger or piston, a pressure device to supply said liquid to each of said lines of pipe, but under different pressures, an overflow stand-pipe, a valve device for allowing the liquid from the pipe having the greatest operative pressure to pass into the overflow-stand-pipe, reducing the pressure in the pipe having the greatest operative pressure, and valve mechanism to admit or cut off a fresh supply of liquid under a high pressure to the pipe having the greatest operative pressure.

3. The combination of a switch or signal, a differential hydraulic operating mechanism for directly operating said switch or signal, two lines of pipe for supplying liquid under different pressures, an accumulator to each of said pipes, but of different powers, an overflow stand-pipe, and a valve device to cut off the stronger accumulator from its pipe and open the pipe to the overflow stand-pipe.

4. The combination of a switch or signal, a differential hydraulic operating mechanism for directly operating said switch or signal, two lines of pipe for supplying liquid under different pressures, an accumulator to each of said pipes, but of different powers, an overflow stand-pipe, a valve device to cut off the stronger accumulator from its pipe and open the pipe to the overflow stand-pipe, a force-pump to supply liquid under pressure to the stronger accumulator, and a supply-connection from the tank to the pump.

5. The combination of a switch or signal, a differential hydraulic operating mechanism for directly operating said switch or signal, two lines of pipe for supplying liquid under different pressures, an accumulator to each of said pipes, but of different powers, a cylinder in the pipe in connection with the stronger accumulator, and a piston in said cylinder re-

ceiving on one side the liquid which extends to the switch or signal and on the other the liquid which extends to the accumulator.

6. The combination of a switch or signal, a differential hydraulic operating mechanism therefor, pipes I, G, and B, including the valve-box D and accumulator C, and pipe M, including the accumulator N, the accumulator N being of less power than M.
- 10 7. The combination of a switch or signal, a differential hydraulic operating mechanism therefor, pipes I, G, and B, including the valve-box D, cylinder H, having the piston h and accumulator C, and pipe M, including the 15 accumulator N, the accumulator N being of less power than M.

8. The combination of a switch or signal, a differential hydraulic operating mechanism therefor, pipes I, G, and B, including the valve-box D and accumulator C, pipe M, including the accumulator N, the accumulator N being of less power than M, overflow stand-pipe T, tank S therefor, pump A for pumping liquid into the accumulator C, and a pipe U to supply liquid from tank S to the pump. 25
